UNITED STATES PATENT OFFICE.

WILLIAM C. BOLGIANO, OF CLEVELAND, OHIO, ASSIGNOR TO THE BROWN HOISTING MACHINERY COMPANY, OF CLEVELAND, OHIO.

GRAB BUCKET.

Application filed March 19, 1924. Serial No. 700,341.

To all whom it may concern:

Be it known that I, WILLIAM C. BOLGIANO, a citizen of the United States, residing in the city of Cleveland, county of Cuyahoga, and State of Ohio, have invented a new and useful Improvement in Grab Buckets, of which the following is a clear and exact description, reference being made to the accompanying drawings, which form part of the specifications, and wherein the same parts are designated by the same numerals in each case.

My invention relates to grab-buckets and particularly to that type known as "clean-up" buckets. Since clean-up buckets require no bucket framing, it is a considerable problem to find ways and means to support and keep, at all times, a perfect alignment of the bucket-opening-rope sheaves and block and the consequent alignment of the bumper or contact parts which it is desirable that such blocks should maintain.

The principal object of my invention is to provide a simple and inexpensive means for supporting the bottom-block of a bucket-opening-rope system and of keeping the same to a predetermined relation with the top-block of said system regardless of what position the scraping scoops may take when the bucket is lowered to the material to be gathered up.

The character of the invention will be easily understood upon reference to the drawings and reading the same in conjunction with the specifications.

In the said drawings, Figure I is a side view, in wide open position, of a grab-bucket which embodies my invention; Figure II is a developed view, in plan, of the bucket opening links; Figure III is a diagrammatic view of the two several rope systems (opening and closing) and illustrates the necessity for the peculiar construction of certain details that are governed by the invention; Figure IV is an enlarged view of the bucket's head and opening links showing the angular relation of the latter and the invention when the bucket is wide open; Figure V is a view of a por-

tion of the opening links showing the angular relation of the same and the invention when the bucket is in its closed position; Figure VI is a developed view, in plan, with certain parts in section, showing the manner in which the sheaves and sheave-cases of the bottom block are supported in their skewed relation to the link hinge-pin; Figures VII and VIII are, respectively, side and vertical sectional views of the sheave-case and its travel-limit bumper, and Figure IX is an end view of the casting that supports the bottom-block sheave in its skewed relation with the bucket-closing link pin.

Referring to the drawings, B is the bucket as a whole; in general it comprises the scoop-members 1, 1, the links 2, 2, 2^a, 2^a, 2^b, 2^b, etc., the top-block 3, and the bottom-block 4, composed of members 4^a, 4^a.

The scoop-members 1, 1, are connected to each other at their inner ends by the hinge-pin 5 which pin also supports the top-block 3. The bucket-opening links 2, 2, 2^a, 2^a, 2^b, 2^b, 2^a, 2^b, are pivotally connected, at their upper ends, to the upper ends of the scoop-members 1, 1, by means of the pins 6, 6, and are of such equal length that when joined together at their other ends by the pin 7, they will have an angular relation one with the other and the apex of the angle thus formed will be directly below the hinge-pin 5, and on the center line of the bucket. The top-block 3 which is supported by the hinge-pin 5, as above stated, contains sheaves 8 and 9 of the bucket-closing system and sheaves 10 and 11 of the bucket-opening system and is provided with a downwardly extending bumping block 3^a.

Approximately midway of the scoop-members, as a whole, are located in pairs, sheaves 12, 12, 12, 12 and are part of the closing rope system. A rope 13, passes downwardly and under the sheave 8 in the top-block 3, thence, as viewed in the drawing, to, over and half-way around one of the sheaves 12 in the left-hand scoop member, thence to, under and half way around one of the sheaves 12 in the other scoop-member,

thence to, over and half-way around the second sheave 12 in the left-hand scoop member, thence to, under and half way around the second sheave 12 in the right hand scoop member, thence to, under and quarterway around the sheave 9 in the top-block 3, thence upwardly to a trolley, where it is dead-ended; the live end going in the bucket at sheave 8 depends from a drum on the trolley. This rope 13, is termed the bucket-closing rope.

In coal and ore handling bridges the hoisting mechanism on the trolley is designed, primarily, to accommodate the digging-bucket, consequently, when a clean-up bucket is also handled by the same trolley its rope leads must be substantially the same as those in the digging bucket, which, in addition to the large sized sheaves required for the large diameter operating ropes make it necessary to skew the sheaves in the top-block and bottom-block (see Figure III) to get the proper rope leads.

To economize in material and room, and, in order to get a compact design of the bucket-opening mechanism, the pin 7 is utilized to support the bottom-block. As will be seen, upon referring to Figure III, sheaves 4^b, 4^b, of the bottom-block members 4^a, 4^a, are skewed to meet the requirements pointed out above, and require specially constructed journal or axle pieces 14, 14, in conjunction with the pin 7, upon which to rotate. Centrally of the shaft 14 is a cylindrical portion 14^a upon which the sheave 4^b is mounted and rotates when actuated by a bucket-opening rope 15. On each side of the central portion 14^a and of lesser diameter and somewhat narrower are sheave-case supports 14^b, 14^b. Next adjacent to the supports 14^b, 14^b, but diagonally opposite, are vertical surfaces 14^c, 14^c. The axle 14 is bored to accommodate the pin 7. This bore is in skewed relation with the axis of the cylindrical portion 14^a and the two axes intersect midway of the axle's length. The axle 14 is cut away at 14^d, 14^d to provide clearance for assembling the sheaves 4^b, 4^b and sheave-cases 16, 16 and, it is provided with bolt holes 14^e, 14^e whereby it can be fastened to the pin 7, by means of suitable bolts adapted to go through the same and through holes that are concentrically located in the pin 7, when the axle 14 is in position on the pin 7.

The sheave-cases 16, 16 are made up of the two plates 16^a, 16^a that are circular in outline, separators 16^b, 16^b, 16^b, bumper-block 16^c, reinforcing plates 16^d, 16^d and keeper bars 16^e, 16^e. The correlation of the several component parts of the sheave-cases 16 is clearly shown in Figures VII and VIII.

The plates 16^a, 16^a are provided with bores or holes 16^f, which are located centrally of

the same, and bolt holes 16^g, which are located near their peripheries. The bore 16^f is slightly larger than the diameter of the portions 14^b, 14^b of the axle 14 and the distances from the center of the bore to the inner edges of the bars 16^e, 16^e are sufficient to insure a proper fit between them and the vertical faces 14^c, 14^c of said axle when they are riveted in place on the plates.

The link pin 7 which supports and joins the links 2, 2, 2^a, 2^a, etc., at their inner ends extends transversely of the bucket and projects through the links 2^a, 2^a far enough to accommodate arms 17, 17, which are fastened to the pin by means of the bolts 18, 18 that are adapted to engage the holes 18^a in the hub of the arm 17 and similar holes in the pin 7 near its ends. A pin 19 is secured to the free end of the arm 17 upon which is mounted a lever 20 that has at the end of its longer arm, which extends outwardly from the pin 19, an inwardly extending link-engaging piece 20^a.

The links 2^a, 2^a are provided at the lower ends and on the upper surface thereof with upwardly projecting lever-engaging fingers 21. The links 2 are provided near their lower ends with lever-retaining plates 22.

As will be obvious certain of the pieces described, the journal or axle pieces 14 for instance, are made separate from the parts with which they are associated, mainly from considerations of construction, or assemblage. By varying the structural principle in certain respects, such pieces may be formed integral with these parts.

Having named and designated with reference characters all the essential details required for the operation of my invention, directions for their proper assembling are now in order and attention is called, particularly, to Figures II and VI. After the bucket proper has been assembled with the top-block 3 in place and the bucket-opening links 2, 2^a, 2^b, etc., pivotally connected at their upper ends to the scoop members 1, 1, the pin 7 is made to engage one of the links 2^a by passing it through the bore of the link; the complementary link 2 is next threaded on the pin and the pin is projected far enough to accommodate one of the bottom-block members 4^a, 4^a. To assemble a bottom-block member 4^a, first place a sheave 4^b on the center or portion 14^a of the special axle 14; next, place a plate 16^a on each of the portions 14^b with the reinforcing plates 16^d up and away from the sheave 4^b, this will bring the keeper-bars 16^e, 16^e next to the faces 14^c, 14^c of the special axle 14 and keep the plates 16^a, 16^a from turning on the axle; the bumper-block 16^c and the separators 16^b, 16^b, 16^b are next inserted between the plates 16^a, 16^a in their designed places and are bolted together by bolts—not shown—that engage the holes 16^f. The pin is now shoved

through the bores of a pair of links 2^b, 2^b then through a pipe separator 23, then through the bores of a second pair of links 2^b, 2^b, then through the bore of the second 5 special-shaft 14, of the second bottom-block member 4^a, then through the fourth pair of link-members, composed of the links 2 and 2^a, respectively, far enough to accommodate one of the arm-members 17. Enough of the 10 pin 7 remains on the entering side to accommodate the second arm-member 17. The special axles or shafts 14, 14 and the arms 17, 17 are then secured to the pin 7 by means of bolts as above referred to: the bumper 15 blocks 16^c, 16^c are directed upwardly and vertically, and the arms 17, 17 bear predetermined right and left angular relations with them. The inwardly extending members 20, 20^a, engage the holes of the plates 20 22, 22 and the shorter arm of the lever 20 engages the finger piece 21 of the link 2^a. As viewed in Figure II the arm 17 on the near end of the pin 7 has an angular relation A (shown in Figures IV and V) with 25 the "center line of bucket" that passes through the centers of the pins 5 and 7, and the arm 17, on the far end of the pin 7, bears a like relation to the vertical "center line of bucket," at the left of such line. 30 When the bucket is suspended by the closing-rope 13, the scoop-members 1, 1, will have been brought together at their digging edges and the angular relation of the pairs 35 of links 2, 2^a—with respect to the vertical center line of the bucket—will be as indicated at C, C in Figure V. To open a bucket of the two-rope type the weight of the bucket is transferred from the closing-rope to the opening rope through a proper manipulation of the brakes and clutches on the 40 supporting trolley.

The bucket-opening-rope 15 is dead-ended in the trolley from whence it passes downwardly to, under and half way around one 45 of the sheaves 4^b in the bottom block 4, thence upwardly to, over and quarter way around the sheave 10 in the top block 3, thence to, over and quarter way around the sheave 11 in the top block, thence downwardly to, under and half way around the 50 second sheave 4^b in the bottom-block, thence upwardly to the winding drum on the trolley.

During the opening or dumping operation 55 of the bucket the angular relation of the pairs of links 2, 2^a, etc., will change from an acute angle D (when the bucket is fully closed) to an obtuse angle E (when the bucket is wide open). While this change in 60 angular relation is taking place the friction set up in the sheave bearings of the bottom-block 4, by the bucket-opening rope 15, tends to rotate the bottom-block, the pin 7 and the arms 20, 20 about the axis of the pin 7. 65 The twisting or tendency to rotate of the

bottom-block 4 is thereupon restrained by levers 20, 20 which are themselves held against rotation about the axis of the pin 7 by links 2, 2 and the fingers 21, 21 on the links 2^a, 2^a. When the twisting is in the 70 direction indicated by the arrow at F, the lever 20 on the near side of the bucket, as viewed in Figure II, is rotated about the pin 19 with reactions at the ends of its longer and shorter arms where they contact with the link 2 and the finger 21 of the link 2^a, respectively; as the bottom-block approaches the top-block the lever 20, rotating about the pin 19, changes its angular relations with the vertical center line of the bucket and the 75 link 2 but holds the arm 17 and the bottom-block 4 to their predetermined relations with the vertical center line of the bucket. During the opening operation the lever 20 on the opposite side of the bucket does not 80 function, and it is held in place by the keeper-plate 22. When the twisting is in the direction indicated by the arrow at G (as when the bucket is being closed), the bottom-block aligning details which are on 85 the opposite side of the bucket, and opposite side of the center line of the bucket, function and the lever 20 on the near side of the bucket is held to its place by its keeper-plate 22. 90

What I claim and wish to protect by Letters Patent is:

1. In a clean-up bucket for overhead trolleys wherein the spade-arm members are revolvably connected to a common cross-pin 100 above, and the bucket opening and closing links are pivotally connected at their upper ends to the inner ends of the scoop-members and, at their lower ends, are revolvably mounted upon a common cross-pin below, the combination of a top-block mounted on the cross-pin above, a bottom-block fixedly mounted on the cross pin below, and means for counteracting any axial movement of the cross-pin below during the vertical movements of said pin and connected links during the opening and closing operations of said bucket, substantially as shown and described. 105
2. In a clean-up bucket for overhead trolleys, the combination of scoop-members oppositely connected at their inner ends by a hinge-pin extending crosswise of said ends, a top-block, containing bucket-opening and closing sheaves; bucket opening and closing links of equal length pivotally connected at 110 one end to said inner ends of said scoop-members at corresponding points thereon, and, at their other ends to a hinge-pin extending cross-wise of said other ends; a bottom-block fixedly seated upon said last named pin containing a freely mounted sheave in alignment with said bucket opening sheave above; bucket closing sheaves operatively mounted on the lower or outer 115 extremities of said scoop-members, a bumper- 120
3. The combination of a top-block, a bottom-block, a common cross-pin, a hinge-pin, a 125 keeper-plate, a lever, a finger, a link, a 130 bumper-block, and a sheave, substantially as shown and described.

block extending downwardly from said top-block, and a bumper-block projecting radially upwards from said bottom-block, together with co-acting means connected to said links and said hinge-pin last above named, for holding said pin against axial movement during its vertical movements in

the opening and closing operations of said bucket, substantially as shown and described.

WILLIAM C. BOLGIANO.
